A. E. GREENE

ELECTRIC INDUCTION FURNACE

Filed Feb. 24, 1920

A. E. Greene
INVENTOR.

UNITED STATES PATENT OFFICE.

ALBERT E. GREENE, OF SEATTLE, WASHINGTON.

ELECTRIC INDUCTION FURNACE.

Application filed February 24, 1920. Serial No. 360,934.

To all whom it may concern:

Be it known that I, ALBERT E. GREENE, citizen of the United States, residing at Seattle, in the county of King and State of Washington, have invented a certain new and useful Improvement in Electric Induction Furnaces, of which the following is a specification.

My present invention relates to the construction and operation of induction furnaces.

One object of my invention is to provide means of passing a large current through a channel containing molten metal and at the same time prevent the metal from contracting due to the effect of excessive current, or at any rate to prevent breaking the molten metal current. There is a difficulty in the operation of an induction furnace known as the "pinch effect" and it may be described as the effect of excessive current on the molten metal tending to make the metal contract and assume a smaller cross section and break the circuit. My present invention avoids this difficulty for I have discovered that the pinch effect may be minimized or avoided by increasing the static pressure on the metal in the induction channels.

One advantage of my invention is that I am able to force a large current through a small cross section of metal and am therefore able to use a small sized furnace in which the lines of force may be made more efficiently to encircle both primary and secondary circuits and therefore able to use a high energy input and yet maintain relatively high power factor.

My invention contemplates a novel construction of induction furnace whereby increased power may be used and great energy developed within a molten conductor constituting the secondary circuit of an induction furnace and yet whereby these results may be accomplished with relatively high power factor. A disadvantage of an induction furnace of large capacity heretofore has been its low power factor and the necessity of correcting the power factor effect by low frequency currents or other means. This disadvantage resulted in part from the considerable distance between primary and secondary circuits and between the core and the secondary. In my present invention, however, I am able to locate

the primary in close proximity to the secondary and am also able to locate the core with relation to the circuits so that there is relatively small amount of leakage flux that does not encircle both circuits.

One feature of my invention relates to the construction of the furnace shell whereby a relatively high head of metal is provided to cause increased pressure on the metal in the channels.

One feature of my invention has to do with the construction of the magnetic core whereby the core comprises part of the furnace shell or serves as a container for the refractory lining.

Another feature relates to the construction of the channels, and other features relate to the primary windings, their construction, the method of controlling the energy development of the furnace and other features which will be more carefully described hereinafter.

The drawings show several modifications of my invention. Fig. 1 is a sectional elevation of an induction furnace built in accordance with my invention. Fig. 2 is a plan view of that furnace. Fig. 3 is another sectional view of this furnace in elevation.

Fig. 4 is a sectional elevation through the center line of Fig. 5 of an induction furnace embodying my invention and Fig. 5 is a plan view of the furnace shown in Fig. 4, and Fig. 6 is an end view in elevation of Fig. 5.

Fig. 7 is a sectional elevation of another modification of my invention and Fig. 8 is a plan view of this furnace and Fig. 7 is a section taken along the line AA of Fig. 2.

With reference to Fig. 1; the primary winding is shown at 1 and the channel filled with metal at 2 and around the channel the refractory lining 3. The refractory lining material is held in the furnace frame and shell and in this modification of my invention the magnetic cores 4 and 5 serve to contain the lining. These magnetic cores are made up of suitable laminations. Fig. 1 shows one of the pressure pipes 6. The primary winding shown in this Figure 1 consists of a water cooled copper tube wound in a suitable number of turns around the legs of the magnetic cores; for example there may be fifteen turns to the coil and it may

be connected to 110 volts. In order to locate the coil close to the secondary I have used water cooling and have also provided an insulating partition 7 above the primary winding and between it and the secondary. The primary may be wound around the side legs of the cores either on the inside of the secondary or on both inside and outside or on any or on all sides of the secondary. I may also insert a metal strip 8 of brass for example between the two circuits to protect the primary from injury from molten metal. The refractory channel consists of suitable material for holding the molten metal. It may be made of silica mixed with clay or other binding material, and if desired this mixture may contain also carbon to make the whole more refractory; or it may be made largely of magnesite or magnesite mixed with carbonaceous material. Outside this refractory and between it and the furnace shell or at any rate outside of the refractory, I preferably place heat insulating material as shown at 9; this serves to keep the heat largely in the molten metal circuit. I preferably make the dimensions of the furnace small so that the two circuits are only a few inches apart and the magnetic circuit is in close proximity to both of them. The magnetic circuit consists of the portion of the core 4 encircling the channel and winding and the magnetic core yoke 5 which makes complete the magnetic circuit. I have shown two separate cores in this Fig. 1 and may use as many or as few as may be desirable from the standpoint of efficiency and cost of construction and operation. I may enclose the refractory entirely in a magnetic core, simply leaving sufficient space to remove the metal from the furnace.

Fig. 2 shows a plan view of this furnace of Fig. 1. The molten metal channel is shown in section lines at 10. The tops of the two refractory pressure pipes are shown at 11 and 12.

Fig. 3 shows still another view of this furnace in sectional elevation along the line AA of Fig. 2 but with the bolts 21 omitted. This view shows the spouts and tap holes for metal and shows the end portions of the shell. These end sections 13 and 14 serve to bolt the laminations of the cores together and to hold them in place. A top shell cover 15 may be used to support and hold the refractory in the pressure pipes. These pipes shown in elevation at 16 and 17 in Fig. 3 may be of any suitable height and higher than needed so that only a part of the total height may be filled with metal and the pressure lessened.

This furnace may be used to pass metal through it continuously by pouring the metal into one of the pressure pipes and allowing it to flow out one of the spouts at a lower

level from the other side of the furnace. Or the metal may be heated and then the furnace tapped out from one of the lower tap holes as at 18; or the furnace may be tilted over and the metal run out.

Other constructions or modifications of my invention involve the use of three phase or polyphase circuits and are shown in the other figures.

In the operation of my invention the power is controlled in any suitable manner such as described in my application for U. S. Patent, Serial No. 740,034, filed January 3, 1913, and it is possible, by reason of maintaining a high head of metal in the pipes 16 and 17 to cause very large secondary currents to flow so as to heat the metal in the channels very rapidly. Thus the induction furnace may be filled with metal from a cupola or other furnace and in a very few minutes, if the induction furnace is hot, the temperature can be raised to any desired increased temperature within limits. If it be desired to pass the metal through the induction furnace continuously this may be done but this process is the subject matter of a separate application for patent.

The modification of my invention shown in Figs. 4, 5 and 6 utilizes pipes for the shell of the induction channels. The pipes are shown in plan in Fig. 5 and the complete channel container consists of four pipe sections 1, 2, 3 and 4. The dotted lines 3 show the channel through the refractory material 6 in the pipes. Sectional view of the refractory is shown in Fig. 4 at 6 where the channels 7 and the containing pipes 1 and 2 are shown in section. Magnetic cores 8 and 9 encircle the pipes and are provided with top yokes 10 and 11 which are removable for removing the pipes without taking them apart. The pipes 1, 2, 3 and 4 are connected at the joints 12, 13, 14 and 15 and thus these sections may be taken apart without taking the core apart. In this way the pipes may be removed and refined and replaced or newly lined pipes may be put back for holding the molten metal. This furnace is shown mounted on trunnions 17 and 18 whereby it may be tilted. Fig. 3 shows another view of the furnace from the end of the furnace and the two terminal pipes are shown at 19 and 20. The pipe 20 may be left closed so that when the furnace is tilted in such a manner as to make the end of the pipe 19 assume the position of maximum elevation, the metal will nevertheless be prevented from flowing out the pipe 20. Thus the furnace may be used to take metal in through the pipe 19 and then may be tilted up to increase the static pressure on the metal in the channels during the heating of the metal when a maximum pressure is desired. The current through the metal in the channel may be controlled

as already described or in any suitable manner. The current may be kept on while the furnace is in horizontal position and the current controlled so as not to cause excessive current to flow. The pipes 19 and 20 may be made as long as desired. Metal may be poured into the furnace through the pipe 19, the metal may be heated as much as desired and then the furnace may be tilted and 10 the metal poured out either all at once or a ladle full at a time.

The channels in these pipes 1, 2, 3, and 4 of Figs. 4 and 5 may be made in any suitable way, for example by ramming the refractory material around cores or forms which may subsequently be withdrawn and the lining of the pipe dried and then inserted in place in the furnace. When assembling the pipes together, suitable mixture of refractory may be placed between the pipes and then they are bolted together to make a good joint suitable for retaining the metal.

The furnace of Figs. 7 and 8 show a further modification of construction.

25 This furnace construction of Figs. 7 and 8 shows the method of placing the lining and cores both inside a suitable container or shell. This container may be made of brick with or without a metal shell. The cores are shown at 1, 2 and 3 in Fig. 8 and in Fig. 7 a top yoke 4 covers the tops of the cores. In Fig. 7 windings are shown diagrammatically at 5 encircling core leg 1, at 6 encircling core leg 2, at 7 encircling leg 3, at 8 and 9 encircling the portions joining the legs 3 and 2 and 2 and 1, respectively, and also at 10 encircling the center leg 2. These all may be water cooled if desired so as to maintain low temperatures in the cores.

40 Channels 11, 12 and 13 are shown. The center channel 11 may be used alone if desired in which case the furnace will operate as a single phase furnace; or the other channels 12 and 13 may be used also in which case 45 the furnace may be operated three phase if desired, one phase for each channel. The static pressure may be maintained by filling the furnace to the desired level or by using pressure pipes as already described. When 50 operating single phase the windings may all be used or any one of them only and they may be operated in series or in parallel. The use of the coils in series or parallel may be for the purpose of varying the number of 55 turns connected to the supply circuit so as to control the power in the furnace all as described in my U. S. Patent No. 1036996 and my application for patent, Sr. No. 740,034, filed Jan. 3, 1913.

60 The shape of channel may be made as desired either wide and shallow, or narrow and deep or round or square. A tapping spout 15 is shown in Fig. 8.

What I claim is;

65 1. An electric induction furnace com-

prising a primary winding, an endless channel in refractory material to contain molten metal and form the secondary circuit of the induction furnace, an auxiliary channel leading down into said first named channel for pouring molten metal into said endless channel, and another auxiliary channel in refractory material leading upwardly from said endless channel at another point thereof for the exit of metal, whereby an increased head of metal may be maintained 75 on the metal in the endless channel while heating the metal therein.

2. An electric induction furnace comprising a primary winding, an endless channel in refractory material and adapted to lie in an approximately horizontal plane for receiving a comparatively small amount of molten metal to form a secondary circuit, and a channel in refractory material 80 communicating with said first-named channel and leading upwardly to contain molten metal and form a head to increase the static pressure on the molten metal in the 85 secondary circuit.

3. An induction furnace for electrically heating molten metal, comprising an endless channel in refractory material, and an auxiliary channel in refractory material 90 communicating with said first-named channel and of small cross-sectional area but sufficient to permit free flow of the molten metal into said first-named channel and another auxiliary channel out of which second channel the metal may leave the furnace, the outlet of said second auxiliary channel being adapted to maintain an increased metal static pressure on the metal 95 in the endless channel while induction heating thereof proceeds.

4. The method of refining metal in an electric furnace which consists in inducing a large electric current through a small volume of metal in a secondary circuit lying 100 in an approximately horizontal plane, and exerting pressure on the molten metal in the said secondary circuit by producing a head with molten metal leading upwardly through an auxiliary channel communicating 105 with said first-named channel.

5. The method of treating metal in an electric furnace which consists in inducing an electric current into molten metal in an 110 endless refractory channel encircling the magnetic core, and causing molten metal to extend through an upright channel and pass out thru another similar upright channel leading from another part of the endless channel, said upright channels being 115 of sufficient height to maintain a head of metal causing increased static pressure on the metal in the endless channel during induction heating thereof.

6. An electric induction furnace comprising a magnetic core and a metal shell 120

- attached to said core in such manner that the laminations of the core together with the metal shell form the container for the refractory lining, said refractory lining forming an endless channel around one leg of said magnetic core.
7. In an electric induction furnace comprising a magnetic core around one leg of which is an endless channel in refractory material, the combination of a part of the magnetic core and shell sections connected with said part of the magnetic core to form together the container for the refractory lining material.
- 10 8. An electric induction furnace comprising an endless pipe interlooping the magnetic core, said endless pipe having refractory material within the same with an endless channel to contain molten metal to form the secondary circuit, and a branch pipe having refractory material and a channel communicating with said first-named channel and leading upwardly to contain molten metal and increase the static pressure on the molten metal in said first-named channel.
- 15 9. In an electric furnace, the combination with a primary circuit, of refractory material having an endless channel there-
- 30 35 40 45 50 55 60 65 70 75 80 85 90 95 100 105 110 115 120 125 130
- in lying in an approximately horizontal plane to contain molten metal and form the secondary circuit, and additional refractory material having therein a channel leading upwardly from said first-named channel to receive molten metal and increase the static pressure in said first-named channel whereby large currents may be induced through a comparatively small amount of metal in the secondary circuit.
10. In an electric furnace, the combination with a primary circuit, of an endless channel in a horizontal plane in refractory material to contain molten metal to form the secondary circuit, an auxiliary channel leading upwardly from such horizontal channel, a spout for pouring the molten metal from said horizontal channel, and an additional spout for pouring the molten metal from said upright channel.
11. In an electric furnace, the combination with a primary circuit, of an endless channel in refractory material to contain molten metal to form the secondary circuit, and a plurality of spaced-apart upwardly extending channels in refractory material to receive molten metal and increase the static pressure on the molten metal in the secondary circuit to permit the latter to have induced therein comparatively large currents.
12. In an electric induction furnace, the combination with a plurality of removable sections of an endless casing, each section being adapted to receive refractory material with a channel therein communicating with the channels of the other sections to form an endless channel for receiving molten metal to form the secondary circuit, a magnetic core interlooping such secondary circuit, and means for increasing the static pressure on the molten metal during the operation of the electric furnace.
13. In an electric induction furnace, the combination with an endless casing containing refractory material with an endless channel therein adapted to contain molten metal to form the secondary circuit, a magnetic core interlooping such secondary circuit, and spaced-apart upwardly extending pipes of refractory material communicating with said endless channel to receive molten metal and increase the static pressure on the molten metal in said channel while comparatively large currents are being induced in such secondary circuit.
14. In an electric induction furnace the combination of a plurality of channels each forming a closed secondary circuit around a magnetic core and means for passing molten metal into one channel and out another whereby the metal passes thru more than one channel in series with each other.
15. An electric induction furnace for continuously heating molten metal while the molten metal passes thru the channels of said furnace, said furnace comprising a channel in refractory material encircling a magnetic core, a vertically extending entrance gate for metal to enter and another vertically extending exit gate in another part of said furnace whereby metal may enter and pass thru said heating channel during heating thereof and meantime an increased static pressure can be maintained on the metal in the secondary induction circuit by means of the head of metal in the exit gate.
16. The process of passing metal continuously thru a furnace which consists in pouring it into an upwardly extending channel connecting with a channel in which the metal may be heated by current induced therein and causing the metal to flow out from another upwardly extending channel from said channel in which the metal is heated inductively thereby causing increased metal head on the portion of the molten metal which is heated inductively.
17. In an electric induction furnace for the heating of molten metal while passing therethru, the combination with an induction heating channel encircling a magnetic core of two or more upwardly extending wells for intake and outflow of molten metal to increase the static pressure on the metal heated.
18. In an electric induction furnace using small channels in refractory material, the combination of a detachable metal shell container for refractory material, a channel for molten metal within said channel form-

ing a part of a single turn secondary transformer circuit, and means of attaching said container to an induction furnace.

19. An electric induction furnace comprising a plurality of vertically extending chambers connected at their lower portions by two or more relatively small channels in refractory material and means of inducing current in the metal in said channels by means of magnetic cores encircling them

and means of causing metal to enter one of said vertically extending chambers and to pass out the other.

In witness whereof I hereunto subscribe my name this 6th day of February, A. D. 1920.
